CLAIM

The ornamental design for a battery cover arrangement, as shown and described.

DESCRIPTION

FIG. 1 is a top perspective view showing the top, front, and right sides of a battery cover arrangement;

FIG. 2 is a bottom perspective view showing the rear, left, and bottom sides of the battery cover arrangement;

FIG. 3 is a front elevation view of the battery cover arrangement;

FIG. 4 is a rear elevation view of the battery cover arrangement;

FIG. 5 is a left side elevation view of the battery cover arrangement;

FIG. 6 is a right side elevation view of the battery cover arrangement;

FIG. 7 is a top plan view of the battery cover arrangement;

FIG. 8 is a bottom plan view of the battery cover arrangement;

FIG. 9 is a bottom perspective view showing the front, right, and bottom sides of the battery cover arrangement wherein the unclaimed subject matter has been removed to illustrate the bottom surface of the battery cover of the battery cover arrangement; and,

FIG. 10 is a bottom plan view of the battery cover arrangement wherein the unclaimed subject matter has been removed to illustrate the bottom surface of the battery cover of the battery cover arrangement.

The portions shown in broken lines show environment and form no part of the claimed design.

1 Claim, 9 Drawing Sheets
